CONVERSION OF HIGHER BOILING
HYDROCARBONS

Arthur E. Pew, Jr., Bryn Mawr, Pa., assignor, by
mesne assignments, to Houdry Process Corpora-
tion, Wilmington, Del., a corporation of Dela-
ware

Application February 15, 1937, Serial No. 125,687

11 Claims. (Cl. 196—49)

The present invention relates to the treatment of composite hydrocarbon materials, such as those occurring in or derived from petroleum, coal, shale or other source, natural or artificial, to produce therefrom valuable hydrocarbons suitable for use as fuel in internal combustion engines, including lower boiling hydrocarbons of the type of benzenes, naphthas, gasolines, kerosenes and the like. More particularly, it is concerned with the production of such lower boiling hydrocarbons from higher boiling hydrocarbons containing both clean, easily vaporizable material or distillate stock and difficultly vaporizable material of the type of heavy distillation residues. A number of pyrolytic or thermal processes for converting higher boiling hydrocarbons into lower boiling hydrocarbons are well known to the art and various systems differing from one another only in minor respects are in common use. A more recent development involves the catalytic transformation of hydrocarbons by a continuous process utilizing two or more converters containing absorbent catalytic material which is periodically regenerated or reactivated, preferably in situ, so that each converter may be alternately on stream and in regeneration, as indicated, for example, in the copending application of Eugene J. Houdry, Serial No. 610,567, filed May 11, 1932, and issued as Patent No. 2,078,247 on April 27, 1937. The pyrolytic systems produce usually, from fresh feed, a lower yield of high anti-knock motor fuel than does the catalytic system but appear to handle partially converted or transformed material with reasonable facility. Because of this facility, many pyrolytic systems involve internal recycling of distillate stocks having clean distillate or gas oil characteristics, obtained, usually, from fractionation of the converted material or synthetic crude leaving the reaction zone. The pyrolytic systems perform at greater efficiency on distillates of the gas oil type than on residual materials of the general type of those remaining from the distillation of crude petroleum. When working on such residues it is often true that the pyrolytic systems can produce motor fuels of good anti-knock rating only under severe operating conditions and at the cost of relatively low yields of desired product with attendant high yields of gas and unconverted residua. The motor fuel so produced sometimes contains relatively large amounts of sulphurous compounds, because of the tendency of sulphur-hydrocarbon compounds to concentrate in residual stocks, and is therefore often quite difficult to refine. The high production of coke reduces

the time efficiency of the system by requiring frequent shut-downs for removing the accumulated coke deposits. The catalytic system, on the other hand, is best adapted to operations where successive residues from transformed material produced in separate, distinct and successive catalyst cracking operations or passes are segregated to provide charging stocks for the separate and successive passes, usually effected at progressively increasing severity of reaction conditions. In general, this system makes its best product in the first pass or when transforming virgin or fresh feed. In the first pass, it produces high yields of high anti-knock motor fuels from residual stocks, as well as from distillates. The motor fuel is easily refined, regardless of the source and characteristics of the charge, and, in addition, the residue remaining after separation of the motor fuel from the transformed products or synthetic crude made in the catalytic system is clean, has characteristics and uses of a gas oil or distillate fuel oil and is suitable for use as a charging stock to a pyrolytic system.

One object of the present invention is to provide a unitary system containing catalytic and pyrolytic reaction zones disposed and arranged so that the advantages of each type of zone are secured and the disadvantages of each minimized or even avoided. Another object is to provide for flexibility of operation. Another object is to realize economies of heat and of equipment. Other objects will be apparent from the detailed discussion which follows.

A concrete embodiment of the invention is set forth diagrammatically in the accompanying drawing or flow chart.

The invention involves a pyrolytic or thermal reaction zone A, shown enclosed by a light full line, and a catalytic reaction zone, enclosed by a broken line, and indicated generally by reference character B, and a single fractionating zone containing fractionator 1. The latter is connected to a source of fresh feed and to both reaction zones A and B and functions coincidentally and cooperatively with both reactions so as:

(1) To provide selected or segregated charging stock for each of said zones, the selected charges comprising

(a) One or more streams of clean higher boiling hydrocarbon distillates which are fed to reaction zone A and

(b) A still higher boiling fraction containing substantially all the difficultly vaporizable or residual hydrocarbons present in the fresh

charge, which fraction is admitted to reaction zone B;

(2) To receive and fractionate the reaction products or synthetic crudes from both reaction zones, after such products have had removed from them substantially all material higher boiling than the charge to zone A or within the boiling range of the charge to zone B, and, optionally, a portion of the material within the boiling range 10 of the charge to zone A, so that,

(a) The selected or segregated distillate or distillates charged to zone A may contain partially converted distillates of restricted and controlled boiling range as well as fresh or virgin stock, and

(b) The charge to reaction zone B is substantially free of partially converted material; and

(3) To provide a stream of desired end point lower boiling hydrocarbons which comprises a 20 blend of substantially all of such material which is present in

(a) The fresh charge and

(b) In the products from both reaction zones A and B.

25 When it is desired to effect complete or substantially complete consumption of fresh feed, the higher boiling material separated from the reaction products may be charged to reaction zone A along with or as an adjunct to the feed to that zone, or, the unitary system may be operated to provide, in addition to the desired end point motor fuel, higher boiling materials of controlled amount and character and having the uses and properties of domestic and Diesel distillate fuels.

30 Referring more particularly to the drawing, fresh charge, which may be, for example, a whole crude petroleum oil or a derivative thereof, such as a topped crude, or any blend or composite mixture of hydrocarbons containing both easily vaporizable and difficultly vaporizable materials which may be made or may occur in refinery practice, is continuously admitted to the unitary system by line 2 and conducted through the latter to heater 3 wherein it is heated to distillation 35 temperature and is then sent through line 4 to fractionating column 1. Any desired portion of the charge may be preheated in heat exchanger 5, located in line 2 and provided with a valved by-pass therearound. From fractionator 1 there is withdrawn one or more higher boiling side stream distillate fractions, as for example, a heavy naphtha by line 6, a relatively light gas oil by line 7 and a relatively heavy gas oil by line 8, the heavy unvaporized residuum is withdrawn 40 from fractionator through line 9. The distillate fraction or fractions are conducted into reaction zone A by suitable branch connections, such as those shown, while the distillation residue withdrawn from fractionator 1 by line 9 is fed to reaction zone B, in which zones the desired conversion takes place.

In some instances, as for example, when the fresh charge bears relatively large amounts of organic sulphur compounds and/or when it contains unusually large amounts of difficultly vaporizable or tarry nature, it is desirable to withdraw a long residuum from fractionator 1 by line 9 containing substantial amounts of the higher boiling distillate portions of the charge. Such 55 practice facilitates handling of the residuum in reaction zone B and provides for reduction in the sulphur content of the desired reaction products. In such cases, heat exchangers 5 or any other suitable equipment for effecting separation from 60 the reaction products of material boiling within

the boiling range of the charge to zone B is operated to condense larger quantities of the synthetic crudes. Such partial condensation may also be regulated so as to avoid recycling through reaction zone A of partially converted material 5 boiling within the boiling range of the heavier portions of the charge to that zone. To this end, the reaction products issuing from the reaction systems may have removed from them components boiling within the boiling range of a portion or even all of the gas oil issuing from fractionator 1 by lines 7 and/or 8 for the purpose of improving the conversion in reaction zone A and/or to provide stock for fuels capable of meeting a wide range of volatility specifications. 15

All lower boiling hydrocarbons of the desired end boiling point made in the unitary system as hereinafter described and any of such hydrocarbons introduced therewith to the fresh charge are withdrawn from fractionator 1 as a single 20 stream or blend by overhead vapor line 23. This blend may be subjected to any desired treatment either before or after condensation. When it is desired to effect direct condensation of the lower boiling hydrocarbons the vapor in line 23 may 25 be condensed in condenser 24 and have fixed or incondensable gases removed therefrom in separator 25 provided with gas outlet 26, hydrocarbon condensate withdrawal line 27 and a connection 28 for removing condensed steam. Any 30 desired amount of condensate may be returned to fractionator 1 by line 29 to be used as reflux, while the remainder may be withdrawn from the system by line 30.

Pyrolytic reaction zone A may contain one or 35 any desired number of systems of any known or desired type for effecting pyrolytic or thermal conversion of higher boiling hydrocarbons in the vapor phase, liquid phase or mixed phase, as for example, utilizing equipment and operating conditions used in the pyrolytic conversion systems 40 commonly known as Cross, Dubbs, tube and tank, De Florez, true vapor phase, gyro, Holmes-Malley, etc. Three such pyrolytic systems are indicated in the accompanying drawing, each comprising a cracking furnace 32a connected by valved transfer line 33a to flash chamber or tower 34a which is provided with a valved residue or tar withdrawal line 35a and a valved vapor outlet 36a. Each of the pyrolytic systems is 45 selectively connected to each of the lines 6, 7 and 50 8 by suitable manifolds and valved branched lines, shown, and to products vapor line 10 by valved vapor outlet 36a.

Although the charge to pyrolytic zone A may 55 be a single stream of distillate, in the interest of high yield of good quality product it is preferable to separately convert a plurality of streams of distillates having restricted or relatively narrow boiling ranges under separate and distinct operating conditions. It is particularly advantageous to separately convert naphtha fractions and gas oil cuts for naphthas generally require more severe reaction conditions (high temperature and/or pressure) than do the higher boiling gas 65 oil cuts. Although partially converted distillates in line 20 may be mixed with one or more of the gas oil cuts issuing from fractionator 1, it is preferable to separately convert the partially converted distillate. The hydrocarbons charged to 70 any of the conversion units or systems in zone A may be subjected to the action of temperatures within the range of 750° to 1200° F. and pressures of from substantially atmospheric or slightly below to 3000 lbs./sq. in. gauge, or more, the 75

pressures and temperatures used in any given system being dependent upon the type of system, and, to some extent, upon the source and characteristics of the charge thereto. The general tendencies are toward: (1) slightly less severe operating conditions with higher boiling range characteristics and/or lower A. P. I. gravities of the charging stocks; and (2) somewhat more severe operating conditions when the charge is comprised to substantial extent of partially converted material.

Pyrolytic systems usually provide suitable apparatus for effecting separation of heavy unconvertible residues from the remaining and clean distillate portions of the reaction products made in the system. Such equipment often takes the form of flash vaporizers which may effect reduction of such residues to coke or which may permit withdrawal of the residues as liquid having controlled characteristics, which liquid may be used as a residual fuel or for the starting material for road oils or asphalts. Flash chambers 34a in reaction zone A are used for this purpose. Each may be operated so that a heavy viscous tarry residue is removed therefrom by valved line 35a, or, in order to meet refinery demands for more fluid residual oils, condensation of the heaviest portions of the vaporous reaction products in transfer line 33a may be effected with the aid, if necessary or desirable, of a suitable cooling fluid which may, for example, be admitted to lines 33a by valved inlets 33c. The resulting condensate is withdrawn as part of the residue. In such instances, the remaining vapors often have an end boiling point within the boiling range of the charge to zone A and can be conducted directly to vapor line 14 by means of manifold 37, shown selectively connected to vapor lines 38a. Thus, each pyrolytic system is selectively connected to fractionator 1 and separator 13 by manifolds 10 and 37 respectively. When a coking operation is conducted in chambers 34a the distillates leaving zone A sometimes have boiling ranges which also permits by-passing of separator 13 by manifold 37.

In a preferred form of the invention, catalytic zone B conforms in general to that disclosed in the aforesaid Patent No. 2,078,247, issued to Eugene J. Houdry on April 27, 1937, and that disclosed in United States Patent No. 2,031,600 issued to J. W. Harrison et al. on February 25, 1936, and comprises: (1) a heater 38b of any desired type for receiving and vaporizing a substantial part of the charge to zone A (2) one or more vessels or separators 39b connected to heater 38b for removing any unvaporized material from the vapors produced in the latter, these separators 39b being provided with vapor and tar outlet lines 40b and 41b, respectively; and (3) two or more converters 42b arranged in parallel and selectively connected to vapor line 40b by line 43b and valved branches 44b. They are also connected to products line 11 by valved branches 50b. Converters 42b may be of any suitable type which provide reaction chambers containing a regenerative adsorptive or catalytic contact mass of any desired type capable of promoting the desired transformation. Preferably, the mass is of a silicious nature and is in com-minged or molded form, comprising, for example, molded pieces composed essentially of a blend of silica and another metal oxide, such as alumina. The blend may be of natural or artificial origin, including colloidal and precipitated gels and activated hydrosilicates of alu-

mina of a clayey nature. Good results are obtained with a catalyst having a weight ratio of silica to alumina in the mass of 3½:1, or more, and other characteristics as disclosed in the co-pending application of Eugene J. Houdry, Serial No. 600,581, filed March 23, 1932 and renewed July 3, 1936 which issued on May 4, 1937, as Patent No. 2,078,945. If desired, the contact mass may contain one or more suitable ingredients, such as metals or metallic oxides, for aiding the transforming reactions and/or the regeneration of the mass by combustion of contaminants deposited thereon during the transformation period, as set forth, for example, in the copending application of Eugene J. Houdry, Serial No. 35,101, filed August 7, 1935, which issued as Patent No. 2,078,951 on May 4, 1937. Converters 42a are preferably conducted and arranged for use alternately on-stream and in regeneration in situ of said catalyst in a manner to permit feeding of a continuous stream of reactant material to the battery of converters, fresh regenerating medium, such as air or other oxygen bearing material being admitted to the converter or converters undergoing regeneration by line 31b and valved branch or branches 45b, while spent regenerating medium is vented from valved branch or branches 46b and line 47b, respectively.

The residue in line 9, preferably while still hot, is admitted to a suitable heater such as tubular heater 38b wherein it is raised to reaction temperature and a substantial portion of it vaporized. In order to assist in such vaporization and to minimize thermal cracking of the residue, as well as to assist in the subsequent catalytic transformation, a suitable inert diluent fluid, such as steam, is admitted to heater 38b, as by line 48b, in amounts which usually lie within the range of 5 to 25% by weight of the heated charge.

The heated stream, after rejection therefrom of unvaporized material in separator 39b, at substantially atmospheric or low superatmospheric pressure, preferably not in excess of 75 lbs./sq. in. gauge, is passed through the contact mass in converters 42b for an operating or run period during which the contact mass is maintained at a temperature within the range of 750° to 925° F.

The reaction products made in either or both of the reaction zones have removed from them any and substantially all material which is within the boiling range of the charge to zone B. One method of effecting such removal is by controlled partial condensation while utilizing a heat exchange medium. According to the drawing, vaporous reaction products leaving zone A, preferably freed of any tar made in that zone, may be conducted by line 10 to line 11, containing vaporous reaction products made in zone B, and passed, with the latter, through heat exchanger 5 into line 12, in heat exchange relation with controlled amounts of cold fresh charge to effect the desired partial condensation. The resulting mixture of liquid and vapors is conducted through line 12 to separator 13. The vapors, containing the desired lower boiling hydrocarbons produced in both reaction zones leave separator 13 by vapor line 14 and are conducted to fractionator 1 to be fractionated with the charge. These vapors may be led by line 14 to line 4 wherein they mix with the heated fresh charge and together with it be admitted to fractionator 1 and/or, all or any desired portion of the vapors in line 14 may be condensed and the

condensate admitted to fractionator 1, preferably at a point above the point of admission of the charge thereto, to serve as a temperature controlling medium after the manner of a refluxing agent to assist in maintaining balanced and controlled operation of fractionator 1. The condensate produced in heat exchanger 5 is withdrawn from separator 13 by line 15. This condensate is clean and possesses other characteristics which render it suitable for use as a distillate, domestic or Diesel fuel oil or as a distillate or gas oil cracking stock. If desired, it may have entrained lower boiling hydrocarbons removed therefrom in steam stripper 16 provided with steam inlet line 17 and vapor outlet line 18 which discharges into vapor line 14. The stripped condensate leaving the stripper 16 by line 19 may be conducted by valved line 20 to reaction zone A to be further converted therein along with or as an adjunct to the one or more distillate streams entering that zone, or all or any desired portion of it may be withdrawn from the system by valved line 21 to be used for fuel oil or any other desired purpose. Stripper 16 may be by-passed by valved line 22 interconnecting lines 15 and 19. It is usually desirable to add additional amounts of inert diluent fluid to the vapors leaving separator 39b, to insure maintenance of vapor phase condition in lines 43b, 44b and in converters 42b. Such addition may be up to 10% by weight of steam, as by line 49b.

In a typical operation of the unitary system wherein a 400° F. end point gasoline is the desired product, a whole petroleum crude, as for example, an East Texas crude may be continuously charged to fractionator 1 and divided therein into straight run gasoline, a heavy naphtha cut having a boiling range of the order of 400 to 500° F. issuing therefrom by line 6, one or more gas oil cuts issuing therefrom by lines 7 and/or 8 and having an end point of about 650° to 700° F., and a residue, leaving the column by line 9, containing substantially all portions of the crude boiling above the end boiling point of the gas oil. The heavy naphtha may be subjected to the action of a temperature of the order of 900° to 930° F. and a pressure of about 1375 lbs./sq. in. gauge for about 90 seconds in the upper pyrolytic system in reaction zone A and the gas oil subjected to the action of a temperature of about 890° F. and a pressure of about 1750 lbs./sq. in. for about three minutes, namely, in the second of the pyrolytic units to effect the desired conversion of these fractions. After removal of the heavy tar therefrom as in flash vaporizer 34a, the synthetic crude vapors produced in the pyrolytic units are vented from zone A into vapor line 10. Meanwhile the residue in line 9 may be admitted to heater 38b and heated to about 890° F., about 15% by weight of superheated steam being added to the residue during the passage through the heater, as by line 48b. The heated residue may then traverse separator 39b and be separated therein into a vapor fraction and a heavy tar having an A. P. I. gravity of the order of 15°. The vapor fraction under a pressure of the order of 15 lbs./sq. in. gauge may then be admitted to one of the converters 42b and passed through a catalyst contained therein and comprising molded pieces of activated hydrosilicate of alumina in which the silica to alumina weight ratio is of the order of 3½:1, having incorporated therewith about 1% by weight of an oxide of manganese as a regeneration promoter and maintained at a temperature

of the order of 860° F. The rate of feed of the vapors to the contact mass may be of the order of 3:4 (3 volumes of condensed vapors per hour to 4 volumes of contact mass). The catalytic synthetic crude is conducted from reaction zone B by line 11, and, along with the vapors in line 10, is subjected to controlled partial condensation by passing the combined vapors in heat exchange relation with fresh charge in heat exchanger 5 so as to produce a liquid fraction containing substantially all portions of the synthetic crude from both reaction zones which boil above the end boiling point of the gas oil cut. The resulting mixture of liquid and vapor may then be passed through line 12 to separator 13, from which the vapors containing all lower boiling hydrocarbons present in both synthetic crudes may be conducted by line 14 to line 4 and thence into fractionator 1, along with heated fresh charge, to be fractionated with the latter. The high boiling condensate in line 15 may be freed of entrained and lower boiling hydrocarbons, as in steam stripper 16, and withdrawn from the system, or, if substantially complete consumption of fresh charge is desired, such condensate may be conducted through line 20 to the lower unit in pyrolytic zone A to be therein subjected to the action of a temperature of the order of 880° F. and a pressure of the order of 1750#/sq. in. gauge for about three minutes. The synthetic crude produced from such condensate after being freed of heavy residue in vessel 34a may be discharged into line 10 along with the other pyrolytic synthetic crudes.

When one of the pyrolytic systems requires cleaning two of the streams of distillate being fed to zone A may be combined and converted together in a single system, thus leaving the one system free for the necessary shutdown without interrupting the operation of the unitary system. For example: if one of two pyrolytic units operating on gas oil cuts requires cleaning, the charge to these two units may be temporarily combined and fed to the unit not requiring cleaning, while making any desired adjustment of the reaction conditions of the unit left in service; when it becomes necessary to clean a unit acting on the naphtha cut the charges to two other two units operating on heavier distillates may be combined as above described and the naphtha stream shifted to the unit thus left off stream.

By the above indicated methods of operation and/or by other methods which are slight variations therefrom, it will be apparent to those skilled in the art that pyrolytic and catalytic zones A and B, respectively, operate interdependently and simultaneously, with maximum utilization of fresh feed, to produce, from the latter, in desired proportions, high quality valuable hydrocarbons of the motor fuel or gasoline type, along with valuable higher boiling fuels of distillate and/or residual types. In all instances, pyrolytic zone A handles only materials which it is capable of acting upon to best advantage, i. e., clean and easily vaporizable stocks, while catalytic zone B transforms only virgin or unconverted material.

By the present invention pyrolytic and catalytic reaction zones for producing high quality lower boiling hydrocarbons from higher boiling hydrocarbons have been combined in a manner that permits each system to operate at high efficiency and to best advantage. The unitary system, which permits substantial economies of heat

and of equipment, also provides for flexibility of operation that allows for yields of lower and higher boiling fuels in proportions suitable for meeting current and local refinery and market 5 conditions of supply and demand. This flexibility is realized with maximum utilization of fresh feed to the system. Furthermore, while maintaining the above advantages, the unitary system provides for production of lower boiling 10 hydrocarbons of high quality, including the ease with which they can be refined, regardless of the characteristics of the original charge.

It is to be understood that the drawing and explanation thereof are only exemplary of the 15 invention. Many minor variations in the equipment and the operation will be apparent to one skilled in the art. Such variations are embraced within the scope of the invention and include among other considerations, various known or 20 desired methods of controlling the temperatures of one or more of the various streams of fluid in the system for purposes of realizing heat and other economies. For example, fresh charge may be utilized to control the temperature of the 25 pyrolytic synthetic crude entering the flash chambers of the pyrolytic zone and/or for controlling the temperature of either or both of the fractions leaving such flash chambers. The invention is applicable, also when a suitable 30 viscosity breaking unit or process is used as an adjunct to the vaporizer 38b for the bottoms cut of fresh charging stock. Vaporizer 38b and separator 39b may be replaced by a contact vaporizer, such for example, as that disclosed in U. S. Patent No. 1,989,927, issued to Eugene J. Houdry on February 5, 1935, or as disclosed in the copending Houdry application, Serial No. 32,170, filed July 19, 1935.

The present invention is, in some respects, 40 generally related to my copending applications Serial Nos. 111,780 and 116,699, filed November 20, 1936 and December 19, 1936, respectively. It is directed, however, to specific features of process and apparatus not involved or claimed 45 in these copending applications, including features for controlling the characteristics of charging material fed to and reaction products obtained from separate pyrolytic and catalytic conversion zones. One of the salient features of the present invention, which distinguishes it from the inventions set forth and claimed in the aforesaid copending applications, relates to interdependent conversion systems and process for operating such systems involving the use of 50 a single fractionating zone for handling both charging material and regulated portions of the reaction products. Further distinctions will be apparent upon reference to the claims in this and the said copending applications.

60 I claim as my invention:

1. In the production of lower boiling hydrocarbons of the motor fuel type, the process comprising feeding to a fractionating zone a charging stock comprising easily vaporizable and difficultly vaporizable higher boiling hydrocarbons, removing from said zone a distillate cut and a residual fraction, said residual fraction containing difficultly vaporizable higher boiling hydrocarbons, subjecting said distillate cut to conditions of pyrolytic conversion to produce therefrom desired lower boiling hydrocarbons of the motor fuel type, subjecting said residual fraction to catalytic cracking conditions including the use of a solid adsorptive contact mass capable of promoting cracking reactions to produce from

said fraction desired lower boiling hydrocarbons of the motor fuel type, separating from products of the pyrolytic and catalytic reactions hydrocarbons boiling within the boiling range of said residual fraction, feeding reaction products remaining after said separation to said fractionating zone to be fractionated therein along with said charging stock, removing a motor fuel fraction of controlled end point from said fractionating zone, subjecting the separated fraction of 10 said products to separate pyrolytic cracking to produce lower boiling hydrocarbons of the motor fuel type, and fractionating products of the last named cracking step in said fractionating zone along with said charging stock and said remaining catalytic and pyrolytic products. 15

2. In the production of lower boiling hydrocarbons of the motor fuel type from a wide boiling range composite hydrocarbon starting material containing both easily vaporizable and difficultly vaporizable hydrocarbons which are above the gasoline boiling range, the steps of process which comprise introducing said starting material into a fractionating zone, therein separating said material into at least two fractions of different boiling range characteristics, a lower boiling or distillate fraction and a higher boiling or residual fraction, said lower boiling fraction being composed primarily of hydrocarbons higher boiling than gasoline, including components within the gas oil boiling range, and said higher boiling or residual fraction containing substantially all of the difficultly vaporizable portions of said starting material, heating and feeding at least a substantial portion of said residual fraction, primarily in vapor phase, to a confined reaction zone containing a solid adsorptive, substantially incombustible cracking catalyst and maintained under conditions so as to effect a conversion or cracking of said higher boiling or residual fraction to substantial extent into lower boiling hydrocarbons of the motor fuel type, passing the aforesaid lower boiling or distillate fraction through a second confined reaction zone while maintaining the same under conditions capable of effecting a pyrolytic conversion thereof to substantial extent into lower boiling hydrocarbons of the motor fuel type, passing a portion only of the reaction products issuing from said reaction zones into the aforesaid fractionating zone, therein to be fractionated in admixture with the aforesaid hydrocarbon starting material, said portion of said products being of controlled boiling range and comprising substantially only hydrocarbons boiling below the boiling range of the aforesaid higher boiling or residual fraction, and withdrawing from said fractionating zone a blend of lower boiling hydrocarbons within the motor fuel range produced in both said pyrolytic and catalytic reaction zones. 50

3. In the production of lower boiling hydrocarbons of the motor fuel type from a high boiling composite hydrocarbon starting material of wide boiling range containing both easily vaporizable and difficultly vaporizable hydrocarbons which are above the gasoline boiling range, the steps of process which comprise separating said starting material into at least two fractions of different boiling range characteristics, a lower boiling or distillate fraction and a higher boiling or residual fraction, said lower boiling fraction being composed primarily of hydrocarbons higher boiling than gasoline, including components within the gas oil boiling range, and said higher 75

boiling or residual fraction containing substantially all of the difficulty vaporizable portions of said starting material, heating and feeding at least a substantial portion of said residual fraction, primarily in vapor phase, to a confined reaction zone containing a solid, adsorptive, substantially incombustible catalytic material and maintained under conditions so as to effect a catalytic conversion or cracking of said higher boiling or residual fraction to substantial extent into lower boiling hydrocarbons of the motor fuel type, passing the aforesaid lower boiling or distillate fraction through a second confined reaction zone maintained under conditions capable of effecting a pyrolytic conversion of the same to substantial extent into lower boiling hydrocarbons of the motor fuel type, separating higher boiling hydrocarbons within the range of the aforesaid residual fraction from remaining components of the products of reaction issuing from said pyrolytic and catalytic reaction zones, blending lower boiling reaction products remaining after said separation with said starting material, and separating from the resulting blend a lower boiling motor fuel of controlled end point while simultaneously producing the aforesaid distillate and residual fractions.

4. In the production of lower boiling hydrocarbons of the motor fuel type, the process of establishing in simultaneous, cooperative and interdependent operating relation a pyrolytic reaction zone and a catalytic reaction zone, each of said zones being capable of and adapted to effect conversion of higher boiling hydrocarbons into lower boiling hydrocarbons, and a single fractionating zone, in the latter continuously dividing a composite hydrocarbon material containing both easily vaporizable and difficulty vaporizable higher boiling hydrocarbons into at least one clean higher boiling distillate fraction and a residual fraction containing substantially all the difficulty vaporizable portions of the charge, feeding said distillate fraction to said pyrolytic zone while maintaining the latter under suitable conditions to effect thermal conversion of said distillate into lower boiling hydrocarbons, vaporizing a substantial proportion of said residual fraction and charging the resulting vapors, substantially free of unvaporized liquids and of extraneous reactant gases, to said catalytic zone maintained under conditions favorable to the production from said residue of high anti-knock lower boiling hydrocarbons, and adsorptive silicious catalytic material being maintained within said catalytic zone, removing the reaction products from each of said zones, separating from said reaction products substantially all hydrocarbons within the boiling range of said residual fraction, feeding the remainder of said reaction products to said fractionating zone to be fractionated along with said charge, removing from said fractionating zone a blend of the aforementioned lower boiling hydrocarbons of the motor fuel type, and feeding the higher boiling hydrocarbons separated from said reaction products to said pyrolytic zone to be therein converted into lower boiling hydrocarbons.

5. In the production of lower boiling hydrocarbons of the motor fuel type from a high boiling composite hydrocarbon starting material containing both easily vaporizable and difficulty vaporizable hydrocarbons which are above the gasoline boiling range, the steps of process which comprise introducing said starting material into a fractionating zone, therein separating said

starting material into at least two fractions of different boiling range characteristics, a lower boiling or distillate fraction and a higher boiling or residual fraction, said lower boiling fraction being composed predominantly of hydrocarbons higher boiling than gasoline, including components within the gas oil boiling range, and said higher boiling or residual fraction containing substantially all of the difficulty vaporizable portions of said starting material, heating said residual hydrocarbon fraction and separating tarry components having a gravity of the order of 15° A. P. I. from the remaining portions thereof, feeding the last-mentioned or remaining portions, primarily in vapor phase, to a confined reaction zone containing a solid adsorptive silicious cracking catalyst and maintained under conditions to effect a catalytic cracking or transformation of the said remaining portions of said residual fraction to substantial extent into lower boiling hydrocarbons including a substantial proportion of components within the gasoline boiling range, passing the aforesaid lower boiling or distillate fraction through a second confined reaction zone while maintaining the same under conditions capable of effecting a pyrolytic conversion thereof to substantial extent into lower boiling hydrocarbons of the motor fuel type, passing products of reaction issuing from each of said confined zones having a boiling range below that of the aforesaid higher boiling or residual fraction into the aforesaid fractionating zone, thereby to be fractionated in admixture with the aforesaid hydrocarbon starting material, and withdrawing from said fractionating zone a blend of lower boiling hydrocarbons composed largely of components within the gasoline boiling range produced in both said pyrolytic and catalytic conversion zones.

6. In the production of lower boiling hydrocarbons of the motor fuel type, the process of establishing in continuous cooperative and interdependent operating relation pyrolytic reaction zones, a single fractionating zone, and at least one catalytic reaction zone containing regenerative silicious contact material capable of promoting transformation of higher boiling hydrocarbons into lower boiling hydrocarbons, heating to distillation temperature a composite hydrocarbon charging material having substantially the boiling range characteristics of a whole crude petroleum oil, feeding said heated charge to said fractionating zone, withdrawing from the latter a heavy naphtha fraction, at least one gas oil fraction and a liquid distillation residual fraction, separately converting said naphtha and gas oil fractions into lower boiling hydrocarbons in individual ones of said pyrolytic zones, effecting vaporization of a substantial portion of said residual fraction, passing the resulting vapors through said silicious contact material within said catalytic reaction zone while maintaining the latter at a temperature within the range of 750° F. to 925° F. to convert such vapors to substantial extent into lower boiling hydrocarbons, withdrawing reaction products from said pyrolytic and catalytic reaction zones, combining said pyrolytic and catalytic reaction products, removing from the combined products substantially all hydrocarbons boiling within the range of said residual fraction, admitting the remainder of said combined products to said fractionating zone to be therein fractionated along with said charge, and withdrawing as product from said fractionating zone a blend of substantially all

- the desired end point lower boiling hydrocarbons produced in said catalytic and pyrolytic reaction zones.
7. In the production of valuable lower boiling hydrocarbons of the motor fuel type, the process of heating to distillation temperature a composite hydrocarbon starting material containing a mixture of both easily vaporizable hydrocarbons of the distillate fuel type and more difficultly vaporizable hydrocarbons of the residual fuel type, feeding the heated mixture to a fractionating zone, withdrawing from said zone a plurality of distillate fractions of differing boiling ranges and higher boiling than the aforementioned motor fuel, and a bottoms fraction containing approximately all of the hydrocarbons in said starting material which boil above 750° F. including said difficultly vaporizable hydrocarbons, heating and vaporizing a substantial proportion of said bottoms fraction and feeding the resulting heated vapors to a reaction zone containing a solid, adsorptive catalytic material, comprising essentially a blend of silica and alumina, to effect transformation of said vapors into high anti-knock lower boiling hydrocarbons, withdrawing reaction products from said catalytic zone and introducing a substantial proportion of said products boiling below the boiling range of said bottoms fraction into said fractionating zone to be therein fractionated along with said starting material, feeding said distillate fractions from said fractionating zone to separate respective reaction zones, each maintained under conditions so as to effect pyrolytic conversion of said distillate fractions into lower boiling hydrocarbons, withdrawing reaction products from the aforementioned pyrolytic reaction zones, removing from the last-mentioned reaction products substantially all hydrocarbons higher boiling than the highest boiling of said distillate fractions, admitting the remainder of said last-mentioned reaction products to said fractionating zone to be therein fractionated along with said hydrocarbon starting material and products from said catalytic reaction zone, and withdrawing from said fractionating zone lower boiling hydrocarbons of the motor fuel type comprising a blend of hydrocarbons produced in both the catalytic and pyrolytic reaction zones.
- 50 8. In apparatus for producing lower boiling hydrocarbons from charging material containing both easily vaporizable and difficultly vaporizable higher boiling hydrocarbons, in combination, a heater for fresh charge, a fractionating column connected to said heater and adapted to effect separation of lower boiling hydrocarbons from higher boiling hydrocarbons and to divide the latter into at least one distillate fraction and a residual fraction, a catalytic transformation system connected to said column so as to receive said residual fraction, said catalytic system comprising heating means for producing hydrocarbon vapors from said residue, a plurality of converters selectively connected to said heating means and containing a body of regenerative, adsorbent contact mass in the form of small pieces of regular sizes and shapes, said converters being adapted and arranged for use alternately in the transformation of hydrocarbons and in regeneration of said mass in place, a pyrolytic conversion system adapted to receive said distillate fraction and providing heating and converting means therefor, means associated with said pyrolytic system for separating and removing from the pyrolytic reaction products substantially all hydrocarbons higher boiling than said distillate fraction to leave a vapor fraction comprising essentially hydrocarbons lower boiling than said residual fraction, means for conducting said vapor fraction to said fractionating column, means for conducting catalytic reaction products from said catalytic system, means for separating and removing as liquid from said catalytic reaction products substantially all hydrocarbons higher boiling than said distillate fraction to leave a vapor fraction comprising essentially hydrocarbons lower boiling than said residual fraction, means for conducting said last named vapor fraction to said fractionating column, and means for conducting said last named liquid fraction to said pyrolytic system.
- 55 9. In apparatus for producing lower boiling hydrocarbons from charging material containing easily vaporizable and difficultly vaporizable higher boiling hydrocarbons, in combination, a heater for heating fresh charge to distillation temperature, a fractionating column provided with an inlet connection, an overhead vapor outlet connection for lower boiling hydrocarbons, at least two side stream distillate connections for higher boiling hydrocarbon fractions of relatively higher and relatively lower boiling ranges and an outlet for distillation residue, a connection from said heater to said inlet connection, at least two pyrolytic conversion systems, a connection between said side stream connection for relatively lower boiling range distillate and one of said systems, a connection between the other of said side stream connections and another pyrolytic system, a catalytic transformation system comprising a heater for effecting vaporization of a substantial portion of said distillation residue, a separator connected to said last named heater for removing unvaporized material from vapors leaving said heater and providing an overhead vapor connection, and a plurality of converters selectively connected to said separator through said last named vapor connection, said converters containing a regenerative contact mass comprising essentially a blend of silica and alumina.

- in molded form and being adapted for use alternately in transformation of hydrocarbons and in regeneration in place, a connection between said residue outlet connection and said last 5 named heater, lines for conducting reaction products from said catalytic system, lines for withdrawing pyrolytic reaction products from each pyrolytic system, means including separating means associated with said pyrolytic systems and with said catalytic system for receiving reaction products therefrom and separating from said reaction products as liquid substantially all hydrocarbons issuing from said systems which 10 are as high boiling as said highest boiling distillate fraction, and vapor connections between said separating means and said fractionating column for conducting the remainder of the reaction products into said column.
- 15 11. In apparatus for producing lower boiling hydrocarbons from charging material containing both easily vaporizable and difficultly vaporizable higher boiling hydrocarbons, in combination, a heater for fresh charge, a fractionating column 20 connected to said heater and adapted to effect

separation of lower boiling hydrocarbons from higher boiling hydrocarbons and to divide the latter into a plurality of distillate fractions and a residual fraction, a catalytic transformation system connected to said column so as to receive 5 said residual fraction, said catalytic system comprising heating means for producing hydrocarbon vapors from said residue, a plurality of converters selectively connected to said heating means and containing regenerative, adsorbent silicious 10 contact mass, said converters being adapted and arranged for use alternately in the transformation of hydrocarbons and in regeneration of said mass in place, a plurality of pyrolytic conversion systems, each one of said pyrolytic systems being connected to said fractionating column so as 15 selectively to receive any one or any desired combination of said distillate fractions, means for removing from the reaction products made in any of said systems hydrocarbons boiling within 20 the boiling range of said residue, and means for conducting the remainder of said products from the last-mentioned means to said fractionating column.

ARTHUR E. PEW, JR. 25

CERTIFICATE OF CORRECTION.

Patent No. 2,197,009.

April 16, 1940.

ARTHUR E. PEW, JR.

It is hereby certified that error appears in the printed specification of the above numbered patent requiring correction as follows: Page 1, second column, line 21, for "charactertstics" read --characteristics--; page 2, first column, line 73, for the word "exchangers" read --exchanger--; page 4, first column, line 30, for "adition" read --addition--; page 6, first column, lines 38 and 42, claim 4, and second column, line 9, claim 5, for "difficulty" read --difficultly--; page 7, first column, line 13, claim 7, for "fractionns" read --fractions--; and that the said Letters Patent should be read with this correction therein that the same may conform to the record of the case in the Patent Office.

Signed and sealed this 18th day of June, A. D. 1940.

(Seal)

Henry Van Arsdale,
Acting Commissioner of Patents.
